Primary Examiner — Lilyana Bekic*Assistant Examiner* — John R Yeh(74) *Attorney, Agent, or Firm* — Leason Ellis LLP(57) **CLAIM**

We claim the ornamental design for a broom, as shown and described.

DESCRIPTION

FIG. 1 is a front perspective view of our design for a broom;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines depict portions of the broom that form no part of the claimed design.

1 Claim, 5 Drawing Sheets(56)
